US0D1024569S

(12) **United States Design Patent** (10) **Patent No.:** **US D1,024,569 S**
(45) **Date of Patent:** **** Apr. 30, 2024**

(54) **POWER SCRUBBER**

(71) Applicant: **Zhongshan Jinshun Household Products Co., Ltd.**, Zhongshan (CN)

(72) Inventor: **Minshi Liang**, Zhongshan (CN)

(73) Assignee: **Zhongshan Jinshun Household Products Co., Ltd.**, Zhongshan (CN)

(**) Term: **15 Years**

(21) Appl. No.: **29/831,790**

(22) Filed: **Mar. 23, 2022**

(51) LOC (14) Cl. **04-01**

(52) U.S. Cl.

USPC **D4/102**; D32/19

Primary Examiner — Karen E Eldridge Powers

(57) **CLAIM**

The ornamental design for a power scrubber, as shown and described.

DESCRIPTION

FIG. 1 is a front, right and bottom perspective view of a power scrubber showing my new design;

FIG. 2 is a left, rear and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, right and bottom perspective view of the power scrubber of FIG. 1, shown in condition of use.

The broken lines in the figures illustrate portions of the power scrubber that form no part of the claimed design.

1 Claim, 9 Drawing Sheets
